UNITED STATES PATENT OFFICE.

FRED C. FANTZ, OF PORT ARTHUR, TEXAS, ASSIGNEE TO THE TEXAS COMPANY, OF NEW YORK, N. Y., A CORPORATION OF TEXAS.

SPRAYING APPARATUS.

Original application filed November 24, 1920, Serial No. 426,215. Divided and this application filed January 16, 1923. Serial No. 612,892.

This invention relates to means for applying fluid coatings.

Difficulty has been experienced in providing suitable apparatus for spraying or applying certain liquids that are characterized by having a tendency to dry or clog up. For example, in the case of such liquids as paint, glue, and the like, there is a tendency for the paint to partially dry about 10 the discharge ports of the apparatus particularly during the periods when the apparatus is not in actual operation. The presence of solid materials or flaky matters in liquids also contributes to the clogging up of the apparatus, since when the flow of liquid is more or less sluggish or is stopped these materials readily collect in the discharge ports. In many cases the applying or spraying of the liquid is carried 20 on under conditions in which more or less dirt or other extraneous matter is present which collects in the discharge ports causing a stoppage of the apparatus. This is particularly true in the case of applying 25 coatings to barrels, casks, and the like, particularly used receptacles in which more or less dirt may be present on the surfaces to be coated, which is rubbed off during the painting or coating operation and collects 30 in the discharge openings causing a clogging of the mechanism.

My invention obviates these difficulties by providing apparatus in which it is practically impossible for the discharge ports to become clogged regardless of how viscous the liquid used may be and even though the liquid have a great tendency to dry up or clog, and moreover under conditions in which considerable dirt or other 40 extraneous matter may be present.

The invention contemplates the provision of a chamber to which the liquid to be applied is admitted. One or more of the walls of the chamber are movable and arranged 45 with contiguous edges which when moved apart form a slot or port for the discharge of fluid. The walls are preferably provided with indentations or recesses along the contiguous edges so that when the walls are closed the indentations form discharge 50 ports, the arrangement being such that the greatest pressure of the fluid may be exerted when the chamber is closed, the passage of

the fluid through the ports under pressure operating to keep same free from obstruction.

The invention is adapted for various uses but inasmuch as it has a particular field of usefulness in the coating or painting of barrels and the like it is described herein as thus applied. For the purpose of this detailed description of the invention reference is had to the accompanying drawings where-
in:

Figure 1 is a plan view showing the apparatus as applied in painting barrels.

Figure 2 is a sectional elevation taken on the line 2-2 of Figure 1.

Figure 3 is an enlarged longitudinal elevation partially in section of the spraying apparatus.

Figure 4 is a cross section taken on the line 4-4 of Figure 3.

In the example of the invention illustrated in Figures 3 and 4 a chamber or reservoir 75 10 is shown which includes a base plate 11 and lateral walls 12 and 13 one edge of each of which is mounted adjacent the base plate 12 and the other edges of which are contiguous.

One or both of the lateral walls 12 and 13 is arranged to be movable. As shown in the drawing the wall 13 is pivotally mounted on pins 14 supported in the end plates 15 which constitute the end closures for the chamber 10. A lever 16 is adapted to operate the movable member 13. The end plates 15 and the fixed wall 12 may be secured to the base plate in any convenient manner, as by means of bolts 17.

The base plate 11 is preferably provided with a groove adjacent the movable member 13 which contains a suitable packing material 18 in order to provide a fluid tight joint between the plate and the movable wall. The edge of the wall adjacent the packing 95 18 is preferably curved, as illustrated, in order that the wall may be readily moved on its axis or hinge.

The adjacent edges of the walls 12 and 13 are equipped with a plurality of indentations which, when the wall 13 is in closed position, constitute discharge ports for the spraying apparatus and through which the paint is ejected in the form of jets or spray. The 105 discharge openings are preferably in the

form of contiguous half circles 19 which form circular openings when the movable member 13 is closed.

In the particular application of the invention illustrated in Figures 1 and 2, a barrel painting or coating machine is shown which includes a suitable supporting frame 20 provided with a skid or runway 21 and rotating means 22 by which the barrel 23 may be rotated during the painting or coating operation. The liquid applying device 10 is mounted adjacent the position of the barrel 23 so that it may be employed in applying the paint or other material used to the surface of the barrel. A plurality of brushes 24 are provided which may well be arranged and adapted to automatically conform to the contour of the barrel, as shown and described in my co-pending application Serial #426,215, filed November 24, 1920, now U. S. Patent No. 1,449,660, of which the present application is a division. The brushing mechanism thus illustrated embodies a plurality of brushes 24 mounted, preferably in staggered relation, on the ends of weighted levers 25 pivotally supported on a pin or rod 26.

The painting or coating operation is carried on over a paint or liquid receptacle 27 which is preferably formed with an inclined bottom 28. A pump 29 is provided having an inlet or suction line 30 which communicates with the liquid in the paint pan and a discharge line 31 leading to the sprayer 10. If desired, the pipe 31 may communicate with the spraying chamber through one or more branch lines, as 31^a and 31^b. As shown in the drawing the pump is adapted to be operated by means of a motor 32, power being transmitted from the motor to the pump shaft by means of a sprocket chain 33 which may also, if desired, be used to transmit power to a hoisting mechanism indicated generally at 34 which may be employed at the conclusion of the painting operation to raise the barrel to an upright position for discharging same, as is more clearly set forth in the co-pending application to which reference has been made. The pan 27 is provided with a screen 35 so arranged that it will catch the bulk of any foreign matter removed from the barrels by the brushes 24 and falling into the pan, permitting only the clean liquid to enter that portion of the pan in which the suction line 30 is positioned.

In operation the pump is preferably kept running so as to keep the paint in circulation, the excess paint removed from the barrel dripping into the paint pan and being picked up by the pump and used again. In this way a minimum quantity of paint is required. If desired, the pump may be equipped with a branch discharge line 36 by which the contents of the pan may be pumped out when desired and it may also

have a branch suction line leading to a suitable source of supply. It is generally satisfactory, however, to introduce the liquid into the pan 27 by means of buckets or other convenient means and then carry on the coating operation by continuously circulating this liquid by means of the pump 29.

A foot lever 37 connected by a link 38 to the lever 16 is provided for opening and closing the hinged spraying mechanism and during the painting operation the operator maintains sufficient pressure on the lever to maintain the movable member in closed position. It is apparent that when the movable member or lip 13 is completely closed that the fluid will be ejected with the greatest amount of force from the chamber 10 through the discharge ports 19 and that as the member 13 is opened the flow of the liquid will be more sluggish. During the periods when the barrels are being discharged from and admitted to the painting machine and when consequently it is not desired to apply the paint, the lip 13 is left open. The paint, however, is preferably continuously circulated by the pump and flows over the edges of the lateral walls 12 and 13 keeping the indentations 19 free from deposits. In cases where the liquid used has a tendency to dry or become solid on exposure to the atmosphere the continual flow of the liquid prevents solidification and in particular prevents the formation of films of solid matter in the discharge ports 19.

It is apparent that the movable wall of the chamber constitutes in effect a gate or valve which controls the discharge of fluid from the spraying mechanism, and in particular regulates the force with which the fluid is discharged so that the fluid may at times be jetted against the surface of the object to be coated and at other times allowed to merely overflow from the chamber. In one form of the invention the indentations on the contiguous edges of the walls of the chamber may be omitted, in which case the fluid will be discharged with greatest force when the movable closure member approaches the closed position, the liquid being then ejected in the form of a film or spray, and the flow of liquid entirely stopped when the movable member reaches the full closed position.

Apparatus of preferred form and construction has been illustrated and described for the purpose of showing a way in which this invention may be used but the inventive thought upon which the application is based is broader than the illustrative embodiment thereof and I, therefore, intend no limitations other than those imposed by the appended claims.

What I claim is:

1. In spraying apparatus, a reservoir comprising a fixed wall having indentations in one of its edges, a complementary movable

- wall having corresponding indentations in one of its edges and mounted to be moved toward and away from the fixed wall to cause the registered indentations to form discharge orifices when the edges are in cooperative engagement, and to provide a large open passage when the edges are disengaged, means for actuating the movable wall into open position to permit the liquid to pass freely through said reservoir or into closed position to effect the discharge thereof through the orifices in jets or spray-like form, and means for forcibly supplying liquid to the reservoir.
- 5 20
- 15 25
2. In spraying apparatus, a reservoir comprising a fixed wall having indentations in one of its edges, a complementary movable
- wall having corresponding indentations in one of its edges and pivotally mounted to be moved toward and away from the fixed wall to cause the registered indentations to form discharge orifices when the edges are in cooperative engagement and to provide a large open passage when the edges are disengaged, manually operated means for actuating the movable wall into open position to permit the liquid to pass freely through said reservoir or into closed position to effect the discharge thereto through the orifices, and means for forcibly supplying liquid to the reservoir.
- 30

In witness whereof I have hereunto set my hand this 4th day of January, 1923.

FRED C. FANTZ.
